(57) **CLAIM**

I claim the ornamental design for a clam shell container, as shown and described.

DESCRIPTION

FIG. 1 is an open perspective view of a clam shell container showing my new design;

FIG. 2 is an open top plan view thereof;

FIG. 3 is an open top side elevation view thereof;

FIG. 4 is a closed top plan view thereof;

FIG. 5 is a bottom closed plan view thereof;

FIG. 6 is a closed side elevation view thereof;

FIG. 7 is a closed front elevation view thereof; and,

FIG. 8 is a closed back view elevation thereof.
